UNITED STATES PATENT OFFICE

LOUIS M. SCHNITZER, OF NEW YORK, N. Y.

DESIGN FOR A WELL ASH TRAY OR LIKE ARTICLE

Application filed November 27, 1931. Serial No. 41,861. Term of patent 3½ years.

To all whom it may concern:

Be it known that LOUIS M. SCHNITZER, a citizen of the United States and resident of New York city, in the county of Kings and State of New York, has invented a new, original, and ornamental Design for a Well Ash Tray or Like Article, of which the following is a specification, reference being had to the accompanying drawings, forming part thereof, in which,

Fig. 1 is a perspective view of a well ash tray or similar article, and

Fig. 2 is a side elevational view thereof.

I claim:

The ornamental design for a well ash tray or the like article, as shown.

LOUIS M. SCHNITZER.
